VACUUM CLEANER

Filed Feb. 27, 1929

UNITED STATES PATENT OFFICE

FREDERICK RIEBEL, JR., OF TOLEDO, OHIO, ASSIGNOR TO AIR-WAY ELECTRIC APPLIANCE CORPORATION, OF TOLEDO, OHIO, A CORPORATION OF DELAWARE

VACUUM CLEANER

Application filed February 27, 1929. Serial No. 342,979.

The present invention, relating, as indicated, to vacuum cleaners, has more specific reference to the floor tools of such cleaners, and its primary object is to provide instrumentalities whereby the vertical position of the suction slot or its associated agitators can be accurately regulated relatively to the surface over which the machine is being operated.

- 10 In one of its embodiments, my invention contemplates providing a vertically movable floor tool with shoes for limiting the descent of the suction slot; and in another embodiment it contemplates providing such a tool
 15 with adjustable stops for limiting the pivotal motion of its floor wheel mountings. In the first mentioned form, the desired function is effected directly by means which contact with the surface over which the machine is being operated, and in the second mentioned form, the desired function is effected by means which predetermine the extent of permitted relative movement between the floor tool and its wheels. The purpose
 20 of both of such embodiments is to enable the operator to select that nozzle position which will adapt the cleaner to the most effective action upon the particular surface under consideration, it being recognized that different surfaces require different nozzle settings for their most satisfactory cleaning. For example, the vertical position of the floor tool suction slot when cleaning such hard and unyielding surfaces as those presented by wood and linoleum should be different from the position of such slot than when cleaning the nap or pile of a rug or carpet. Similarly, when cleaning and aerating the relatively long nap of an Oriental or like rug, the suction slot and its associated agitators should have a different setting than when the same operations are being carried out on the usually shorter nap of a carpet. Accordingly, and as above stated, it is my present object to provide a single or unitary floor tool of such construction that the suction slot and its cooperating agitators (if used) can be preliminarily adjusted to whatever vertical position such parts should have for the most efficacious and

satisfactory use upon the various types of surfaces presented by the materials to be cleaned.

To the accomplishment of the foregoing and related ends, said invention, then, consists of the means hereinafter fully described and particularly pointed out in the claims; the annexed drawing and the following description setting forth in detail certain structure embodying the invention, such disclosed means constituting, however, but one of various mechanical forms in which the principle of the invention may be used.

In said annexed drawing:

Fig. 1 is a longitudinal section through a vacuum cleaner floor tool embodying one form of the present improvements; Fig. 2 is a transverse section through a complete floor tool which was taken along a plane indicated by the line 2—2 of Fig. 1; Fig. 3 is a view similar to Fig. 2 which was taken along a plane indicated by the line 3—3 of Fig. 1; Fig. 4 is a fragmentary bottom plan view of a vacuum cleaner floor tool embodying another form of the present improvements; Fig. 5 is a vertical longitudinal section which was taken along the line 5—5 of Fig. 4; and Fig. 6 is a vertical section which was taken transversely of a complete floor tool along a plane indicated by the line 6—6 of Fig. 5.

That embodiment of my invention illustrated in Figs. 1 to 3, inclusive, comprises certain improvements which are shown in association with a vacuum cleaning nozzle or floor tool consisting of a body having a cavity 10 for connecting the slot 11 with the suction tube opening 12, parallel grooves 13 for receiving the upper portions of the agitators 14, and end sockets 15 for housing the wheel mountings 16, each mounting 16 comprising a pair of arms 25 and 26 respectively, the former being hereinafter referred to as a tang and the latter as a spring. The agitators 14 have their upper portions 17 removably secured within the grooves 13 by means of the transversely extending screws 18, and the bottom surfaces of their inturned lower portions 19 are provided with inclined scorings 20, such scorings desirably form-

ing triangular shaped teeth or projections 21. The wheels 22 are mounted upon stub shafts or axles 23, and such axles project laterally from the downturned ends 24 of the tangs 25.

5 To the inner ends of such tangs, the corresponding ends of the springs 26 are riveted or otherwise secured, and these springs are outwardly extended to provide suitable manipulating portions 27, such portions being centrally perforated as at 28. Normally, the springs 26 make a rather wide angle with the tangs 25, but when such springs are manually compressed or flexed downwardly, the wheel mountings constituted by such parts 15 and the tangs 25 can be readily introduced into the sockets 15. When such mountings are thus positioned, the tangs may be permitted to move downwardly and into contact with the surfaces 29, and similarly the 20 springs 26 may be permitted to move upwardly into contact with the surfaces 30, the assembly thereby effected being maintained by the screws 31 projecting into or through the openings 28.

25 Without going into details, it may be mentioned that this invention is particularly adapted for use in connection with vacuum cleaners of the type shown and described in U. S. reissue Patent No. 16,224, and in U. S. 30 Patent No. 1,416,876. Such machines are so constructed that raising of the handle is automatically effective to place additional weight upon the springs 26 and to move the socket surfaces 29 downwardly and out of contact 35 with the tangs 25, thus allowing the entire floor tool to assume a lower position with respect to the surface over which the machine is being operated. Ordinarily, the extent to which such tool thus descends is dependent 40 upon the characteristics of the surface or material being cleaned, but due to variations in the quantity of dust and dirt in the collecting bag, to differences in the height to which various operators will lift the handle, and 45 to the continually changing speeds and directions of movement of the cleaner as a whole, intended compensatory changes in the vertical position of the floor tool do not always occur. Therefore, this invention contemplates providing the screws 31 with adjusting heads 32, such heads having skirt portions 33 which are adapted to form indexes for cooperating with scales or the like 34, such scales being constituted by peripheral 55 markings on the upstanding bosses 35. Since the lower ends of the screws 31 are long enough to bear against the upper surfaces of the tangs 25, it is apparent that the vertical position of such screws will be effective to 60 predetermine the extent to which such tangs can pivotally move arcuately around their inner ends. It will also be apparent that by suitably adjusting such screws, the lowermost position of the floor tool can be regulated in 65 any manner made necessary or desirable by

the specific surface to be cleaned, and that the scales and indexes afford a convenient guide for reference purposes as well as for enabling the operator accurately to adjust both ends of the tool to the same height. If desired, the adjusting screws or their head portions may be provided with means for maintaining any selected setting, although unless the lead angle of the threads is uncommonly large such means will not ordinarily be necessary as a sufficiently close thread fit will accomplish the same purpose.

70 In Figs. 4 to 6, inclusive, another embodiment of my invention is shown in association with a floor tool which in most respects is identical with the floor tool described in connection with Figs. 1 to 3, inclusive. Instead, however, of the screw adjustment shown in Figs. 1 to 3, a common spring retaining screw 36 is employed in the present embodiment, and the adjusting or regulating means takes the form of a shoe 37, such shoe having a bearing portion 38, guide portions 39, and a slotted shank 40. Such shank, as best shown 75 in Fig. 6, may be adjustably clamped against the end wall 41 by means of a suitable set screw 42, this screw affording a convenient means for permitting of the vertical adjustment of the bearing portion of the regulating shoe relatively to the bottoms of the agitators 43. It will be understood that both ends of the floor tool are similarly equipped, and that the bearing faces of the shoes may have any width or length made necessary by the character of their intended function—the predetermined 80 of the lowermost position to which the floor tool can descend by flexure of the springs constituting a part of the wheel assembly.

85 Other modes of applying the principle of my invention may be employed instead of the one explained, change being made as regards the structure herein disclosed, provided the means stated by any of the following claims or the equivalent of such stated means be employed.

90 I therefore particularly point out and distinctly claim as my invention:—

95 1. In apparatus of the class described, the combination of a tool having end sockets, mountings in said sockets, said mountings having arcuately movable wheel carrying parts extending outwardly beyond said sockets, and means mounted in the sockets for adjustably controlling such arcuate movement.

100 2. In apparatus of the class described, the combination of a tool having sockets, mountings in said sockets, said mountings having arcuately movable wheel carrying parts extending outwardly beyond said sockets, and means extending through the walls of said sockets for adjustably controlling such arcuate movement.

105 3. A vacuum cleaner comprising a floor

tool including sockets in its end portions, a pair of floor wheels, mounting devices each including a tang to one end of which a respective floor wheel is journalled and an apertured leaf spring secured to its opposite end extending toward and spaced above the wheel carrying end, said mounting devices being received in the respective sockets with said springs in engagement with the upper walls 10 of the socket, and adjusting screws threaded through the upper walls of the sockets, projecting through said apertures, and positioned to engage said tangs to limit movement thereof toward said springs.

15 4. A vacuum cleaner comprising a floor tool including sockets in its end portions, a pair of floor wheels, mounting devices each including a tang to one end of which a respective floor wheel is journalled and an apertured leaf spring secured to its opposite end extending toward and spaced above the wheel carrying end, said mounting devices being received in the respective sockets with said springs in engagement with the upper walls 20 of the socket, and adjusting screws threaded through the upper walls of the sockets, projecting through said apertures, and positioned to engage said tangs to limit movement thereof toward said springs, and adjusting screws including means for determining the adjustment thereof relative to the sockets.

25 5. A vacuum cleaner comprising a floor tool including sockets in its end portions, a pair of floor wheels, a pair of mounting devices each comprising a tang to one end of which a respective floor wheel is journalled and an apertured spring secured to its opposite end extending toward and spaced above the wheel carrying end, said mounting devices being received in the respective sockets with said springs in engagement with the upper walls 30 thereof, bosses formed on said upper walls and projecting upwardly, said bosses being provided with scale faces, and adjusting screws threaded through said bosses, extending through said apertures, and positioned to engage said tangs to limit movement thereof toward the springs, and adjusting screws including depending skirts receiving the upper portions of said bosses and co-acting with said scale faces to determine the adjustment of the screws relative to the sockets.

Signed by me, this 8th day of October,
55 1928.

FREDERICK RIEBEL, JR.
